UNITED STATES PATENT OFFICE.

FRITZ SCHULZ, OF CHICAGO, ILLINOIS, ASSIGNOR TO THE GOOD MANUFACTURING CO., OF CHICAGO, ILLINOIS, A CORPORATION OF ILLINOIS.

BRICK-TONGS.

No. 806,197.

Specification of Letters Patent.

Patented Dec. 5, 1905.

Application filed April 10, 1905. Serial No. 254,728.

To all whom it may concern:

Be it known that I, FRITZ SCHULZ, a citizen of the United States, residing at Chicago, in the county of Cook and State of Illinois, have 5 invented certain new and useful Improvements in Brick-Tongs; and I do hereby declare the following to be a full, clear, and exact description of the invention, such as will enable others skilled in the art to which it applies 10 to make and use the same.

My invention relates to a novel construction in a lifting-tongs, the object being to provide a simple, efficient, adjustable device of this character; and it consists in the features of construction and combinations of parts hereinafter fully described and claimed.

In the accompanying drawings, illustrating my invention, Figure 1 is a central longitudinal section of a lifting-tongs constructed 20 in accordance with my invention. Fig. 2 is a vertical transverse section of the same on the line 2 2 of Fig. 1. Fig. 3 is a detail transverse section on the line 3 3 of Fig. 1.

My invention has for its particular object 25 to provide a lifting-tongs which is exceedingly cheap and durable and which can be readily adjusted to grasp objects of various widths. To this end I provide a pair of tongs A and B, both of which are made of sheet 30 metal bent so as to give said tongs a U-shaped form in cross-section, the flanges thereof thus serving as reinforcing-ribs to render the tongs exceedingly stiff. Each of said tongs is substantially L-shaped, the shorter 35 arms C and D thereof forming jaws between which the object to be lifted is adapted to be clamped. Secured at one end to said jaw D, adjacent the inner end thereof, is a chain E, the free end of which passes through a sleeve 40 F, mounted in said jaw C of the member A and between the prongs of a fork G, secured to the latter, and which is adapted to engage said chain to determine the relative positions 45 of said tongs, the point of juncture of said chain E with the jaw D and the mouth of the sleeve F forming substantially fulcrums upon which said jaws turn. Said sleeve F and the fork G comprise a casting which is secured in said jaw C by means of rivets or the like, said 50 jaw C being provided with an opening for the passage of the mouth portion of said sleeve F. The longer arm H of said member A is of less width than the longer arm J of the member B and is adapted to fit within the latter.

The said arm J of said member B is bent between its ends, as at K, such bent portion constituting a fulcrum upon which the arm H of the member A is adapted to turn and partially slide longitudinally to open and close, so to speak, said jaws C and D. 55

My said device is particularly adapted for handling bricks, although it may obviously be employed for practically any purpose for which lifting-tongs are used and is operated as follows: Assuming that the operator is 60 handling bricks and desires to lift and transport a given number of same at a time, the chain E is first adjusted to bring said jaws into relative position substantially equal in distance apart to the combined width of the 65 number of bricks desired to be handled at each operation, said chain being then brought into engagement with the fork G and the free end portion thereof laid into the longer arm H of said member A, where it will not interfere 70 with the operator. The said longer arms H and J of said members A and B are then grasped in both hands on either side of the fulcrum K of said member B. By tightening the hold on the free end portion of the 75 arm H of the member A and releasing the pressure on the free end of the arm J of the member B said free end portion of the arm H will be depressed into said arm J and the jaws C and D thereof opened preparatory to 80 being inserted over the bricks or other object to be lifted. After said jaws have been so inserted the pressure on the free end of the arm H is released and the tongs lifted by the free end of the arm J of said member B, 85 such action serving first to contract said jaws to engage such bricks or other object and causing the latter to be lifted with said tongs, the weight of the object itself serving to hold 90 said jaws firmly engaged, the pressure exerted by said jaws being greater as the weight 95 of the bricks or object lifted increases.

The device is very cheap, light, durable, simple, and efficient.

I claim as my invention—

1. A lifting-tongs comprising two jaw members movable telescopically relatively to each other, a chain or the like connecting said members and serving to limit their relative movement in one direction, and serving 100 at its point of juncture with said jaw members as fulcrums upon which the latter turn.

2. A lifting-tongs comprising two L-

shaped jaw members movable telescopically relatively to each other, a chain or the like secured to the jaw portion of one member and adapted to engage locking means on the other thereof to hold said members against relative movement in one direction and serve as fulcrums upon which said jaw portions turn.

3. A lifting - tongs comprising two L-shaped jaw members movable telescopically relatively to each other, a chain or the like secured to the jaw portion of one member and adapted to engage locking means on the other thereof to hold said members against relative movement in one direction and serve

as fulcrums upon which said jaw portions turn, the interfitting portions of said members forming stems for actuating said jaw portions to turn the same, and one of said stem portions being provided between its ends with a fulcrum upon which the other stem turns.

In testimony whereof I have signed my name in presence of two subscribing witnesses.

FRITZ SCHULZ.
